UNITED STATES PATENT OFFICE.

MAX MILLER, OF NEW YORK, N. Y.

MEANS FOR FORMING CONCRETE PILES.

1,296,995.

Specification of Letters Patent. Patented Mar. 11, 1919.

Application filed May 10, 1916. Serial No. 96,547.

To all whom it may concern:

Be it known that I, MAX MILLER, a citizen of the United States, and a resident of the city of New York, borough of the Bronx, in 5 the county of Bronx and State of New York, have invented a new and Improved Means for Forming Concrete Piles, of which the following is a full, clear, and exact description.

10 This invention relates to the forming or sinking of concrete piles or the like and has particular reference to means or methods of forming concrete piles *in situ* with an enlargement either at the lower end or at some 15 point above it, forming a footing or pedestal to increase the stability and the efficiency of the pile when built or sunk in soft earth.

Among the objects of the invention, therefore, is to provide an improved means for 20 forming a hole having an enlargement at or near its lower end to receive the concrete or other pile forming material. By the term "concrete", as used herein, I mean to cover any suitable plastic material, either with or 25 without metal reinforcements for the formation of the pile. The term "pile" furthermore is to be understood as being applicable to any analogous foundation or supporting element.

30 Another object of the invention is to provide means for forming concrete piles *in situ*, the piles having pedestals or enlargements formed thereon, in connection with means for excluding soft earth from the pile hole.

35 More definitely stated, this invention contemplates the provision and use of a casing to be driven into the earth either with or independently of a core, said casing being provided with an expandable section adapting 40 that portion of the casing to be spread or enlarged after being driven, the expandable section, however, being so constructed that irrespective of the expansion it remains practically continuous or unbroken in its contour, 45 whereby the soft earth is prevented from entering the space formed within it.

With the foregoing and other objects in view the invention consists in the arrangement and combination of parts hereinafter 50 described and claimed, and while the invention is not restricted to the exact details of construction disclosed or suggested herein, still for the purpose of illustrating a practical embodiment thereof reference is had to 55 the accompanying drawings, in which like

reference characters designate the same parts in the several views, and in which—

Figure 1 is a front elevation of one form of my invention indicating especially the expandable section in its driving form or position, a portion being broken away to indicate the manner of construction; 60

Fig. 2 is a vertical central section of the structure of Fig. 1, showing the parts, however, after expansion of the expandable sec- 65

Fig. 3 is a transverse sectional detail on the line 3—3 of Fig. 1;

Fig. 4 is a vertical sectional detail on the line 4—4 of Fig. 1; 70

Fig. 5 is a view similar to Fig. 1, but showing a slight modification;

Fig. 6 is another modification indicating a closed lower end or driving point;

Fig. 7 is a form of the invention in which 75 the casing is of corrugated metal and provided with a driving point;

Fig. 8 is a view indicating the action of the expanding means on the lower open end of the corrugated casing; 80

Fig. 9 is a plan view indicating the cross sectional form of a corrugated pipe or casing;

Fig. 10 is a transverse section on the line 10—10 of Fig. 8;

Fig. 11 is a horizontal sectional detail of 85 another modification.

As above premised, in the practice of concrete piling it is frequently desirable and essential that a footing or pedestal be formed upon the lower end of the pile, and to this 90 end many attempts have been made to provide a method or means for accomplishing this result economically and in a dependable manner. In other words, whereas it is old

to drive or sink a metal casing to the depth 95 desired and then resort to ramming, percus- sion or an explosion to form an enlarged hole at or below the lower end of the casing, all these expedients so far as I am aware in

my extensive experience are more or less un- 100 reliable for various reasons, among which may be noted, the force required in the ram- ming of concrete at the lower end of a hole is liable to be exerted mainly in one direction

and thus an unsatisfactory footing is pro- 105 vided. Again, where an enlarged hole is at- tempted to be formed by explosion or the like, it is difficult and practically impossible to proceed with the work with any sense of

accuracy or precision as to the size or form 110

of the enlargement thus attempted to be made. Moreover, in all of these operations soft earth or mud is likely to tumble or flow into the hole thus formed, and thus either exclude the concrete from the enlargement or mix therewith forming a faulty result.

The means I employ, therefore, in the making of concrete piles includes a casing which may be integral throughout or may 10 be made up of a plurality of joints or sections to be driven in succession, each succeeding section being slipped upon the previously driven parts. Furthermore, the casing proposed by me may be driven either in 15 connection with or independently of any well known or approved form of core which may be afterward withdrawn.

Referring now to Figs. 1 to 4, I show a casing as comprising an expandable section 20 15 constituting an advancing section of the casing and having an open bottom or lower end. This section is composed of any suitable number of overlapping upwardly tapered segments, the inner segments being 25 indicated at 16 and the outer segments at 17. In the driving position these segments are disposed in cylindrical form and are so held at their lower and intermediate portions by any suitable number of bands 18 30 and 19 arranged on the inside and outside respectively of the section. These bands are preferably arranged in pairs, one band 18 of each pair being directly within the outer band 19 of the same pair, see Figs. 3 35 and 4. Any suitable means may be provided to hold these bands from premature movement up or down, especially during the driving operation. To this end, I employ double headed pins 20 extending transversely 40 and radially through the segments 16, and lying between adjacent outer segments 17.

The inner band is open or provided with abutting ends, as indicated at 21. The purpose of the bands is primarily to prevent the 45 collapse of the expandable section during the driving action, and hence the inner band 18 is much heavier than the outer band. The tendency of the section to expand during the driving action is counteracted by the 50 reaction of the surrounding earth and the outer bands. The outer band being lighter than the inner band may be made solid and may be ruptured during the expansion of the section.

55 To facilitate the driving action the segments of one series are preferably longer than those of the other.

The upper ends of all of the segments are centrally connected as by rivets 22 to one 60 another or to one or more solid rings 23 forming an inexpansive crown.

A driving section 24 of any suitable length has slip joint connection at 25 with the upper edge and inner surface of said 65 crown. If a plurality of sections 24 be

used, each of them will be applied to the next preceding section in the same manner. After the complete casing including the expandable section is driven to the desired depth, a depth whose extent will be precisely known because of the length of the several sections, the earth within the same is mucked or dredged out by any suitable means, leaving a clear hole to the bottom of the expandable section. I then expand the 70 lower end thereof as suggested in Fig. 2. The bands 18 do not resist this expansion since they are adapted to slip beneath the heads of the pins 20. The section 15 thus expanded remains in place whether the other section 24 of the casing be removed or not, and since the lower ends of the segments 16 and 17 are wider than the upper ends and still overlap each other when expanded, the hole within the expandable section will remain practically clean and free from any material, such as sand, mud or earth that would tend to produce a defective footing or pedestal for the concrete pile, which may then be formed by the introduction of concrete in any usual or well known manner, and by this means a pedestal of definite size and shape will always be formed.

The structure in Fig. 5 differs from that 95 above described, in the provision of inner segments 16' which are rectangular, while the segments 17 only are tapered.

The expandable section 15' (Fig. 6) comprises a crown 23, the same as in the other 100 forms, but the segments 16' and 17' are all of double tapered form. In other words, they are widest at their middles and tapered toward both their upper and their lower ends. Said lower ends of the tapered segments are all rigidly connected to one another and to one or more solid rings 23', to which is secured a thimble 25' providing a connection with a driving point or cup 26. Bands 18 and 19 of the same nature and for 105 the same purpose as above described are employed around the expandable portion of this section also, to stiffen the section and prevent collapse thereof during the driving action or after the core, if one is used, has 110 been withdrawn. The expansion of this form of the device is similar to the first described form and is such that a double conical hole for a pedestal of corresponding 115 form, as suggested by the dotted and dashed lines, although the expansion will be carried to a much greater extent than thus indicated. The hole formed in this manner will be practically free from water, as well as other materials, and since the driving point 26 remains in place and the lower end of the expandable section is retained in 120 place therewith, no water can enter the lower end of the casing.

In Fig. 7, the casing 24' is of corrugated 125

metal, the corrugations extending from end to end, making a very strong structure so far as the driving action is concerned, and this form may include a driving point 26^a 5 connected thereto by means 28^a and 25^a similar to the means shown in Fig. 6. This form of casing is adapted to be expanded above its point or lower end like the form of Fig. 6, and as in that case also, the casing will be 10 waterproof, there being practically no openings between the point and the upper end.

In Fig. 8 the casing 24^b is corrugated as above stated, but the body thereof is straight instead of tapered, as shown in Figs. 6 and 15 7. The lower end of the casing is open, as in Figs. 1 to 5, and hence may be expanded like the other open bottomed devices. This casing 20 obviously may be either single or sectional, the several sections being connected, as shown at 25^a.

Referring again to Fig. 5, it may be noted that the segments 16' may be independent of one another, the same as the segments 16 of the other forms, but in some instances I prefer that the adjacent segments 16' be not wholly separated, but simply scored, as shown at 16^b in Fig. 11. The dotted lines indicate the form of the metal flat, in which form the scoring may be done by any suitable means and then when the device is bent in tubular form the scoring will be practically closed, as shown in full lines. In this form of the invention, the inner series of segments or the tubular construction which 35 after expansion forms the inner series of segments, is vastly stiffer than the other forms, and therefore has great strength in resisting the tendency to collapse during the driving action.

40 The term "section" as employed herein is intended to apply to any definite portion of the casing considered longitudinally and particularly to the expandable portion, whether the expandable portion be made of 45 a separate part or as an integral part of a non-sectional casing.

I claim:

1. Means for forming concrete piles comprising a casing to be driven into the earth, 50 said casing having at its lower end an expandable portion normally of the diameter of the casing adapted to be expanded after it is driven to the desired depth, said portion after being expanded presenting a continuous surface to positively exclude the entrance of earth through the sides thereof.

2. Means for forming a concrete pile with an expanded footing or pedestal, the same comprising a casing including a portion 60 comprising a plurality of vertical overlapping segments, means connecting the upper ends of said segments and constituting a solid non-expandable crown, the segments

below said crown being movable radially of the casing to expanded form. 65

3. The herein described means for forming a pedestal pile, the same comprising an expandable section normally of cylindrical form including a plurality of independent vertical segments and non-expandable means 70 connecting the upper ends of said segments, and means engaging and co-operating with the segments below their upper ends to prevent collapse thereof while being driven.

4. The herein described expandable section for a pile casing, the same being normally of cylindrical form and comprising a plurality of vertical segments, a non-expandable device connecting the upper ends of the segments and forming a crown, the segments below the crown being movable radially below the crown, and means carried 80 within the segments serving to prevent collapse during driving but providing for expanding action after being driven. 85

5. The herein described expandable section for a pile casing, the same comprising a plurality of inner and outer series of vertical segments, means connecting all of the upper ends of said segments forming a non-expandable crown, the segments below the crown being movable radially outwardly below the crown, and means carried by one of said series of segments and engaging the other segments to prevent the collapse of the section 95 while being driven but providing for the expansion thereof after being driven.

6. The herein described expandable section for a concrete pile casing, the same comprising a plurality of inner and outer vertical segments, non-expandable means connecting the upper ends of the segments, the segments being movable outwardly radially below said non-expandable means, a pair of bands disposed opposite each other within 100 and without the expandable portion of the segments, and means carried by certain of said segments and projecting between adjacent segments of the remainder thereof to hold said bands from upward or downward 105 displacement, but permitting of expansion thereof along with the expansion of the section.

7. Means for forming a concrete pile with an expanded footing or pedestal, the same 115 comprising a casing having an expandable section comprising a plurality of vertical segments, means connecting the upper ends of said segments and constituting a non-expandable crown, the segments below said 120 crown being expandable radially of the casing to provide an enlarged hole of definite predetermined size and form, and means to prevent the collapse of the expandable section during the driving of the casing.

MAX MILLER.
